Primary Examiner — Marissa J Cash*Assistant Examiner* — Altaira J Swangin(74) *Attorney, Agent, or Firm* — Foley & Lardner LLP(57) **CLAIM**

I claim the ornamental design for a cake holder, as shown and described.

DESCRIPTION

FIG. 1 is a top, right perspective view of a cake holder, showing the claimed design;

FIG. 2 is front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines formed by dashes of equal lengths, within the top surface of the cake holder in FIG. 1 and FIG. 6, illustrate portions of the cake holder that form no part of the claimed design. The additional set of broken lines formed by dashes of unequal lengths, on the sides of the cake holder in FIG. 1, FIG. 4, and FIG. 5, is directed to environment and forms no part of the claimed design.
